(57) **CLAIM**

The ornamental design for a drain cleaning tool, as shown and described.

DESCRIPTION

FIG. 1 is a perspective view of a drain cleaning tool showing our design;

FIG. 2 is an enlarged perspective view thereof;

FIG. 3 is a left side elevational view thereof;

FIG. 4 is a right side elevational view thereof;

FIG. 5 is a front view thereof;

FIG. 6 is a rear view thereof;

FIG. 7 is a top plan view thereof; and,

FIG. 8 is a bottom plan view thereof.

The broken line showing of the details of FIGS. 1-5 and 7-8 is included for the purpose of showing environmental portions of the drain cleaning tool and forms no part of the claimed design.
